Patented Aug. 3, 1920.

UNITED STATES PATENT OFFICE.

JOHN W. COAST, JR., OF TULSA, OKLAHOMA, ASSIGNOR TO THE PROCESS COMPANY, A CORPORATION OF MARYLAND.

ART OF CRACKING HYDROCARBONS.

1,348,265.

Specification of Letters Patent.

Patented Aug. 3, 1920.

Application filed March 22, 1917, Serial No. 156,646. Renewed June 14, 1920. Serial No. 389,007.

To all whom it may concern:

Be it known that I, JOHN W. COAST, Jr., a citizen of the United States of America, a resident of Tulsa, in the county of Tulsa, 5 State of Oklahoma, have invented certain new and useful Improvements in the Art of Cracking Hydrocarbons, of which the following is a full, clear, and exact description, reference being had to the accompanying drawing, forming a part of this specification.

My invention relates to improvements in the art of cracking hydrocarbons, and more particularly to a method of protecting stills from the injurious effects of coke or tarry 10 coke-forming substances.

The ordinary cracking still for treating high boiling point petroleum products is provided with means for condensing and returning heavy fractions for further treatment in the still. This reflux condensate comprises relatively light fractions which, by repeated distillation, may be converted into the desired low boiling point product. However, it also includes a large percentage 25 of heavy coke-forming fractions which usually drop to the bottom of the still and accumulate thereon at points where the still is subjected directly to the action of the intense heat. This coke or carbon is produced 30 partly by heavy fractions in the reflux condensate and partly by other fractions which do not vaporize in the still. It prevents the free transmission of heat from the still bottom to the liquid contents of the still, and 35 when a sufficient quantity has been accumulated, the still bottom becomes red hot. Some immediate steps must then be taken to avoid a rupture at the overheated portion of the still. In actual practice, the coke accumulates on the hot still bottom while the oil in the still is maintained at a high temperature and under a high pressure, thus rendering the cracking operation quite dangerous.

45 The main object of my invention is to prevent a large body of the coke, or tarry coke-forming substances, from accumulating in a single pill at a point where the heat is transmitted to the still. In the preferred 50 form of the invention, this is accomplished by condensing the high boiling point fractions and conducting such condensate to a point where it will not be subjected directly to the intense heat at the still bottom. The 55 relatively heavy coke-forming fractions are

prevented from circulating to the hottest part of the still, the lighter fractions of the reflux condensate being permitted to circulate freely in the liquid contents of the still. I thus effect a separation of the 60 lighter hydrocarbons from the coke forming matter in the reflux condensate permitting the lighter hydrocarbons to be re-vaporized and retarding the coke at a point where it will not interfere with the transmission 65 of heat through the still bottom.

Figure I is a diagrammatic view of a cracking apparatus adapted for use in carrying out my method.

Fig. II is a transverse section of the still 70 taken approximately on the line II-II, Fig. I.

The still 1, arranged above a heating chamber 2, is connected by means of an air-cooled vapor pipe 3 to a reflux condenser 4. 75 5 designates a vapor pipe leading from the reflux condenser to a main condensing coil 6 from which the low boiling point product is recovered. The condensing coil 6 is preferably arranged in a water tank 7. 8 designates a return pipe for conducting reflux condensate from the condenser 4 to the still. The air-cooled vapor pipe 3 constitutes a reflux condenser, and it is inclined to allow the condensate to flow backwardly to the 85 still.

The apparatus I have shown is particularly adapted for use in cracking high boiling point products of distillation, such, for example, as the distillates or residues resulting from the distillation of crude petroleum. The substances to be treated are introduced into the still in any suitable manner, and any desired pressure may be obtained by regulating a valve 9, preferably located in the vapor pipe 5. The pressure in the still is preferably greater than 50 pounds per square inch, and the temperature of the contents of the still preferably ranges from about 600° F. to 800° F. Heat 100 generated in the heating chamber 2 is transmitted directly through the still bottom to the liquid contents of the still. The low boiling point vapors passing from the liquid flow through the vapor pipe 3 and reflux 105 condenser 4 to the pipe 5, leading to the main condenser 6. The relatively high boiling point fractions are condensed in the vapor pipe 3 or in the condenser 4, such fractions being returned either through the 110

vapor pipe 3 or return pipe 8. This reflux condensate includes a large percentage of heavy coke-forming fractions commingled with lighter fractions, which may be redistilled to form part of the low boiling point product.

In the preferred form of the invention the end portions of the still bottom are seated upon the walls 10 of the heating chamber, and these walls protect said end portions from the intense heat of the heating chamber. The heat is transmitted directly through the middle portion of the still bottom, and the protected end portions of the still are maintained in a relatively cool condition. Diverging conductors 12 lead from a funnel 13 to coke pockets 14 at the ends of the still bottom. The funnel 13 lies directly below the vapor dome at the upper portion of the still, where it will receive the reflux condensate discharged from the pipes 3 and 8. Dams, or obstructions, 15 are preferably arranged on the still bottom to positively prevent the heavy coke-forming fractions from reaching the points at which the heat is transmitted to the still. The coke is thus trapped and confined on the protected end portions of the still bottom, where it will not interfere with the transmission of heat to the liquid contents of the still. The relatively light fractions of the reflux condensate circulate freely from the coke pockets 14 and commingle with the liquid in the still. The coke in the pockets

14 is not materially agitated by the circulation of the liquid in the still, and owing to its weight it does not float or rise in the lighter liquid.

The coke pockets are preferably formed below the surface of the liquid in the still so as to permit the relatively light fractions to circulate from the coke, and the conductors 12 are preferably submerged in the hot liquid so that the returning condensate will be heated before it reaches the coke pockets.

I claim:

In the art of cracking petroleum hydrocarbons, the method which comprises confining such hydrocarbons in a still, transmitting heat directly to the middle portion of the still bottom, maintaining the end portions of the still bottom in a relatively cool condition, maintaining the contents of the still under pressure, conducting vapor from the still to a main condenser, also condensing the high boiling point fractions and conducting such condensate through the liquid contents of the still and depositing it on the relatively cool end portions of the still bottom, preventing the relatively heavy coke-forming fractions of said condensate from circulating away from said relatively cool end portions, and permitting the lighter fractions of said condensate to circulate freely in the contents of the still.

In testimony that I claim the foregoing I hereunto affix my signature.

JOHN W. COAST, JR.
